TAPPING TOOL

Joseph Starkel, Chicago, Ill.

Application May 3, 1947, Serial No. 745,749

5 Claims. (Cl. 10—147)

1

This invention pertains to a machine tool, and more particularly to a tapping tool and the like.

In many instances when threads must be applied to a work piece, they must be applied manually with a tapping tool. Unless the tool is carefully handled there is danger that the tap will become damaged or broken even where a pilot hole is first made, as by a drill, thus causing unnecessary delay and expense.

It is, therefore, an object of this invention to provide an inexpensive tapping tool which may be used with the tool making the pilot hole in the work piece to be threaded, thus insuring that the path of the tap will follow the path of the tool making the pilot hole.

Another object of the invention is to provide a tapping tool which is inexpensive, rugged and easy to operate and maintain.

Another object of the invention is to provide a tapping tool or similar tool which can be used with conventional taps or similar tool members.

Another object of the invention is to provide a tapping tool which is adapted to be carried in a relatively small, convenient package, yet one which provides adequate leverage in use for easy operation.

Another object of the invention is to provide a tapping tool which is simple and rugged, and wherein the wearing parts are reduced to a minimum.

With these and various other objects in view, the invention consists of certain novel features of construction and operation as will be more fully described and particularly pointed out in the specification, drawings and claims appended hereto.

In the drawings, which illustrate embodiments of the device and wherein like reference characters are used to designate like parts—

Figure 1 is a fragmentary elevation of a drill press having a tapping tool embodying the invention applied thereto;

Figure 2 is an enlarged fragmentary elevation of the assembled tapping tool embodying the invention;

Figure 3 is an enlarged fragmentary elevation of the tap end portion of the tapping tool illustrated in Figure 2, the same being taken substantially in the plane as indicated by the line 3—3 of Figure 2;

Figure 4 is an exploded, fragmentary, sectional elevation of portions of the tapping tool embodying the invention, the elevation being taken at the tap end of the tool;

Figure 5 is an enlarged sectional plan view

2

taken substantially in the plane as indicated by the line 5—5 of Figure 3;

Figure 6 is an enlarged, sectional plan view taken substantially in the plane as indicated by the line 6—6 of Figure 3; and

Figure 7 is an enlarged, sectional plan view taken substantially in the plane as indicated by the line 7—7 of Figure 3.

The tapping tool illustrated comprises the relatively fixed cylindrical pivot bar or rod 10, the upper or chuck end 12 of which is adapted to be secured in the chuck 14 of a machine, such as the drill press 16 illustrated in Figure 1, the chuck being adapted to be raised and lowered in the conventional manner by the handle 18. It is, of course, understood that the tapping tool may be used in other forms of machines, the drill press being herein illustrated merely by way of example.

20 The lower or tap end 20 of the bar 10 is shouldered or cut away as at 22 providing the cylindrical portion 24 which merges into the frustoconical portion 26 provided at its extremity with the substantially spherical or rounded portion 28. The junction or ridge 29 between portions 26 and 28 is substantially of the same diameter as the diameter of rod 10. Thus a guiding and pivoting recess 30 is provided at the end 20 of the bar 10.

25 The rotatable body member 32 is provided with the upper tubular member 34, having an inner diameter slightly greater than the outer diameter of the bar 10 whereby pivotal movement with preferably small tolerance is had between the body member 32 and bar 10 when in assembled relation.

30 The tubular member or tube 34 is provided with the cross-bar or operating head 35 internally threaded as at 38 and 40 for receiving corresponding male threaded members 42 and 44 on the removable handles 46 and 48, said handles being identical and of sufficient length to provide adequate leverage for operation of the tool. The head 35 is formed integral with, is brazed, welded or otherwise suitably secured to the tube 34.

35 The lower or tap end of the tube 34 is shouldered as at 36, as by cutting away a part of the end of said tube, and the tube is formed integral with, is brazed, welded or otherwise suitably secured to the lower socket member 50.

40 The socket member 50 and the tube 34 are apertured as at 52 and the socket member 50 is apertured as at 54, said apertures being in vertical alignment and being adapted to respectively 45 receive the inwardly extending lugs 56 and 58,

said lugs being spring pressed inwardly by the leaf spring 60 to the ends of which said lugs are secured, said spring being secured intermediate the ends thereof as at 62 to the socket member 50.

A cylindrical adapter 64 is provided for receiving a tap, bit or other member 66, the upper end of the adapter 64 being shouldered as at 68 to provide a lug similar to lug 36 whereby when the adapter, the outer diameter of which is slightly less than the inner diameter of the member 50, is inserted in the member 50, shoulders 68 and 36 will interlock as shown in Figure 3, the adapter being provided with the notch 70 adapted to receive the lug 58 when in applied position, whereby the tap 66 is releasably secured to the body member 32.

As an illustration of the use of the herein described tool, let it be assumed that the drill press 16 has been utilized to drill a small pilot hole in a work piece (not shown) the pilot hole to be later used for guiding a tapping tool 66 for threading the work piece. The drill is removed from the chuck 14 which is moved to raised position. The handles 46 and 48 are applied to the cross bar 35 and the bar 10 is inserted in the upper part of tube 34 until the lug 56 is in engagement with the recess 30. As the lug 56 is near the tap end of the body member 32 a long bearing is provided between the bar 10 and the body member, tending always to maintain axial alignment.

The adapter 64 provided with the tap 66 is inserted in the socket member 50 in the position illustrated in Figure 3, where the shoulders 36 and 68 interlock and the lug 58 is received in the notch 70. Adapter 64 and body 32 being non-rotatably connected results in axial alignment of the tool and tap being maintained at all times. The tapping tool thus assembled is then applied to the chuck so that the upper end 12 of bar 10 is secured in the chuck 14. The handle 18 can then be operated to lower the tapping tool 66 until it is adjacent the pilot hole of the work piece. The exact distance of the tap from the pilot hole is a matter of choice, but it has been found convenient to have enough clearance so that if it is necessary to change a tap, there is room enough to do so without operation of handle 18. Where the handle 18 is set so room is provided, the adapter 64 may be pulled downwardly and disengaged from the socket 50 without having to change the position of the drill press 16, and a new tap 66 may be applied.

With the tap in this raised position, downward pressure on the handles 46 and 48 will cause the spring pressed lug 56 to move downwardly from the pivoting recess 30, sliding over the portion 26 and ridge 29 as the body member 32 moves downwardly and the tap 66 enters the pilot hole. The body member 32 slides downwardly on the bar 10 and is maintained in alignment with it.

As the tapping operation proceeds through rotation of the handles 46 and 48 the tap 66 penetrates deeper into the pilot hole and the body member moves downwardly on the bar 10. There is no need to alter the position of the press 16 to compensate for this downward movement as the long bearing between bar 10 and body member 32 permits the required downward tapping movement. It is apparent that during rotation of the handles while tapping, the bar 10 and chuck 14 remain stationary and the body member 32 rotates freely around the bar 10.

On completion of the tapping operation the body member 32 is raised by the handles 46 and 48 until the lug 56 is again received in the pivoting recess 30 holding the body member 32 in raised position. Handle 18 may then be operated to raise the tapping tool for release from chuck 14.

With the device illustrated it will be seen that the tapping tool follows exactly the path of the drill or other tool which made the pilot hole, thus insuring a proper path of movement of the tapping tool, preventing its being forced out of its proper path which would break or otherwise render the tapping tool 66 useless.

It is to be understood that this application is not to be limited by the exact embodiments of the device shown, which are merely by way of illustration and not limitation as various and other forms of the device will, of course, be apparent to those skilled in the art without departing from the spirit of the invention or the scope of the claims.

I claim:

1. In a tapping tool, the combination of a body member comprising a socket member, a tubular member secured thereto and extending into said socket member terminating therein, a cross head secured to said tubular member in spaced relation to said socket member, handles removably secured to said cross head in opposed axially aligned relation to each other, the end of said tubular member within said socket member having a shoulder, spring pressed lugs movably disposed within said socket, on opposite sides of said shoulder urged diametrically of said socket member, said lugs being aligned axially of said socket member, a pivot bar having one end removably inserted into said body member from the end opposite to said socket member, said end of said pivot bar within said tubular member having a recess for receiving one of said lugs whereby said body member is pivoted to said pivot bar, the inner diameter of said tubular member being slightly greater than the outer diameter of said bar whereby a bearing is provided between said bar and body member, the opposite end of said bar being adapted to be held in a chuck for positioning the tapping tool during operation thereof, and an adapter provided with a tap, removably inserted into said socket member and provided with a shoulder interlocked with said first named shoulder whereby rotation of said body member rotates said tap, said adapter having a recess for receiving the other lug whereby said shoulders are held in interlocked position.

2. In a tapping tool, the combination of a body member comprising a socket member, a tubular member secured thereto, a cross head secured to said tubular member in spaced relation to said socket member, handles removably secured to said cross head in opposed axially aligned relation to each other, a shoulder within said socket member, spring pressed lugs movably disposed within said socket member and urged toward the axis thereof, a pivot bar having one end inserted into said body member from the end opposite to said socket member, said end of said pivot bar within said body member having a recess for receiving one of said lugs whereby said body member is pivoted to said pivot bar, the inner diameter of said tubular member being slightly greater than the outer diameter of said bar whereby a bearing is provided between said bar

and body member, the opposite end of said bar being adapted to be held in a chuck for positioning the tapping tool during operation thereof, and an adapter provided with a tap, said adapter being removably inserted into said socket member and provided with a shoulder interlocked with said first named shoulder whereby rotation of said body member rotates said tap, said adapter having a recess for receiving the other lug whereby said shoulders are held in interlocked position.

3. In a tapping tool, the combination of a body member comprising a socket member, a tubular member secured thereto and extending into said socket member terminating therein, a cross head secured to said tubular member in spaced relation to said socket member, handles removably secured to said cross head in opposed axially aligned relation to each other, the end of said tubular member within said socket member having a shoulder, spring pressed lugs movably disposed within said socket on opposite sides of said shoulder urged diametrically of said socket member, said lugs being aligned axially of said socket member, the spring of said spring pressed lugs comprising a leaf member secured to said socket member intermediate the ends of said leaf member, the lugs being secured to the ends of the leaf member, a pivot bar having one end removably inserted into said body member from the end opposite to said socket member, said end of said pivot bar within said body member having a recess for receiving one of said lugs whereby said body member is pivoted to said pivot bar, the inner diameter of said tubular member being slightly greater than the outer diameter of said bar whereby a bearing is provided between said bar and body member, the opposite end of said bar being adapted to be held in a chuck for positioning the tapping tool during operation thereof, and an adapter provided with a tap, said adapter being removably inserted into said socket member and provided with a shoulder interlocked with said first named shoulder whereby rotation of said body member rotates said tap, said adapter having a recess for receiving the other lug whereby said shoulders are held in interlocked position.

4. In a tapping tool, the combination of a pivot bar having one end adapted to be fixed for positioning the tapping tool during operation thereof, a recess adjacent the other end of said bar, an elongated body member position in axial alignment with said bar and mounted for pivotal and longitudinal movement with respect thereto, a spring pressed lug carried by said body member for engaging said recess and releasably holding said body against longitudinal movement with respect to said bar, an adapter provided with a tap releasably fixed to said body member and means for rotating said body member mounted thereon.
- 15 5. In a tapping tool, the combination of a body member, a tap-holding adapter member inserted into one end of said body member, a spring pressed lug on one of said members and a recess in the other of said members for releasably securing said members together, a pivot bar member having one end inserted in the other end of said body member, said body member being pivotally and axially movable with respect to said bar member, a spring pressed lug on one of said last named members and a recess in the other of said last named members for releasably and pivotally securing said members together, the opposite end of said bar member being adapted to be held in a chuck for positioning the tapping tool during operation thereof, and means for rotating said body member mounted thereon.
- 20 25 30
